INVENTOR:
SIDNEY J. HEIMAN.

BY Arthur C Eckert
ATTORNEY.

UNITED STATES PATENT OFFICE

SIDNEY J. HEIMAN, OF ST. LOUIS, MISSOURI

OIL BURNER

Application filed October 23, 1930. Serial No. 490,597.

The object of my invention is to devise an improved oil burner. In the conventional type burner now in use, a considerable time interval is necessary between the lighting of the burner and its successful functioning. Furthermore, when the conventional burner operates, it produces carbon which, when entrained in air, forms smoke. This is particularly true in the burning of heavy oils of low volatility. Among the specific objects of my invention are those which obviate these defects. More specifically, my device comprises means for initially burning the more volatile portions of the oil and utilizing the heat of combustion thus obtained for subsequently igniting and burning the heavier portions of the oil. In my device an improvement is made of few and simple parts, which lend themselves readily to multiple production and may be easily and cheaply manufactured and installed or repaired.

With these and other objects in view, my invention has relation to certain novel features of construction and arrangement of parts as will be hereinafter more fully described and pointed out in the claims and illustrated in the drawings.

Fig. 1 is a plan view of the conventional oil burner with my improvement shown.

Fig. 2 is a front elevation of the structure shown in Fig. 1.

Fig. 3 is an elevation of my specific improvement to an oil burner.

Numeral 4 indicates a cast cylindrical cup having the tapped hole (5) in its center and the peripheral flange (6). The supply pipe (7) is in threaded engagement in the tapped hole (5). Numeral 8 designates a perforated sleeve having perforations (9). Numeral 10 designates a cylindrical cap having the top (11) and depending flange (12). In the cylindrical cup 10 is formed a central opening co-axial with the pipe 7. Numerals 13 designate rods passing through perforations in the top (11) and through holes in the ears (14) which are formed integral with the cast cylinder cup (4). There are a plurality of such rods (13). By means of nuts (15) the perforated sleeve (8) and the cylin-

drical cap (10) and the cast cylindrical cup (4) are secured in frictional engagement. On the supply pipe (7) in space relationship with the bottom of the cast cylindrical cup (4) is secured the imperforate disc (16). 55 There is no fluid communication between the supply pipe (7) and the imperforate disc (16). The open end of the supply pipe (7) terminates in the bottom of the perforated disc (17). In operation by static, pressure 60 or otherwise, the oil is forced upward through the supply pipe (7) on to the perforated disc (17). The lighter portions of the oil are consumed on this disc while the heavier portions pass through the perforations of the disc and fall on to the imperforate disc (16) and bowl of cup (4) where 65 they are consumed. The heat and flame from both discs is confined in the perforated sleeve (8) and the cast cylinder cup (4) 70 and the cylindrical cap (10). The flame and heat also pass upwardly and outwardly from the cylindrical cap (10).

The operation may be further described as follows:

When the oil reaches the perforated disc (17) it is ignited by some external means such as a torch or by any mechanical ignition device. The first oil to burn is the lighter oil. Before the flash point of the heavier oil has been reached, it will have passed through the perforations in the disc (17) on to the imperforate disc (16). The heat of combustion of the lighter portions of the oil is such as to ignite and perfectly burn the heavier portions of the oil that have fallen on the imperforate disc (16). By these means the initial lighting is facilitated because the lighter oil has the lower flash point or kindling temperature, and the production of carbon and smoke is either eliminated or minimized because the proper oxygen supply is present for combustion for both the light and heavy oil and this supply is had in the presence of sufficient heat to crack and break down the oil to a gas or vapor before being burned. The idea of the entire device is to burn gas that has been generated from oil instead of oil directly.

What I claim is:

1. An oil burner comprising in combination, a cylindrical cup having a tapped hole in its center, and having a peripheral flange, a fuel supply pipe secured in the tapped hole of said cylindrical cup, a perforated sleeve positioned within the peripheral flange of said cylindrical cup, a cylindrical cap positioned on said perforated sleeve, rods passing through perforations in said cylindrical cap, and through holes formed in ears, which in turn are formed on said cylindrical cup, for securing said cup, perforated sleeve and cylindrical cap together, an imperforated disc secured to said fuel supply pipe, between said cylindrical cup and said cylindrical cap and in spaced relationship therewith. 2. An oil burner comprising in combination, a cylindrical cup having a tapped hole in its center, and having a peripheral flange, a fuel supply pipe secured in the tapped hole of said cylindrical cup, a perforated sleeve positioned within the peripheral flange of said cylindrical cup, a cylindrical cap positioned on said perforated sleeve, rods passing through perforations in said cylindrical cap, and through holes formed in ears, which in turn are formed on said cylindrical cup, for securing said cup, perforated sleeve and cylindrical cap together, a perforated disc secured to said fuel supply pipe permitting oil under pressure from the fuel supply pipe to overflow into said perforated disc, and being strained there through said imperforated disc positioned between said cylindrical cup and said cylindrical cap. 3. An oil burner comprising in combination, a cylindrical cup having a tapped hole in its center, and having a peripheral flange, a fuel supply pipe secured in the tapped hole of said cylindrical cup, a perforated sleeve positioned within the peripheral flange of said cylindrical cup, a cylindrical cap positioned on said perforated sleeve, rods passing through perforations in said cylindrical cap, and through holes formed in ears, which in turn are formed on said cylindrical cup, for securing said cup, perforated sleeve and cylindrical cap together, a perforated and an imperforated disc secured in spaced relationship to said fuel supply pipe, between said cylindrical cup and said cylindrical cap and in spaced relationship therewith. 4. An oil burner comprising in combination, a cylindrical cup having a tapped hole in its center, and having a peripheral flange, a fuel supply pipe secured in the tapped hole of said cylindrical cup, a perforated sleeve positioned within the peripheral flange of said cylindrical cup, a cylindrical cap positioned on said perforated sleeve, rods passing through perforations in said cylindrical cap, and through holes formed in ears, which in turn are formed on said cylindrical cup, for securing said cup, perforated sleeve and cylindrical cap together, an imperforated disc secured to said fuel supply pipe, but not in fluid communication therewith, a perforated disc in spaced relationship with said imperforated disc, said perforated disc secured to said fuel supply pipe above said imperforated disc, said perforated and imperforated disc positioned between said cylindrical cup and said cylindrical cap. 5. An oil burner comprising in combination, a cylindrical cup having a tapped hole in its center, and having a peripheral flange, a fuel supply pipe secured in the tapped hole of said cylindrical cup, a perforated sleeve positioned within the peripheral flange of said cylindrical cup, a cylindrical cap positioned on said perforated sleeve, rods passing through perforations in said cylindrical cap, and through holes formed in ears, which in turn are formed on said cylindrical cup, for securing said cup, perforated sleeve and cylindrical cap together, a perforated disc secured to said fuel supply pipe permitting oil under pressure from the fuel supply pipe to overflow into said perforated disc, and being strained there through said imperforated disc positioned between said cylindrical cup and said cylindrical cap.
